United States Patent

Des. 238,311

Patented Dec. 30, 1975

238,311

COMBINED LIPSTICK AND CASING THEREFOR

Ted I. Kingsford and Jayne H. Greene, Memphis, Tenn.,
assignors to Plough, Inc., Memphis, Tenn.

Filed Mar. 15, 1974, Ser. No. 451,648

Term of patent 14 years

Int. Cl. D28—02

U.S. Cl. D86—10 G

FIG. 1 is a perspective view of a combined lipstick and casing therefor showing our new design.

FIG. 2 is an exploded perspective view from beneath. The sides not shown are mirror images of those shown.

We claim:

The ornamental design for combined lipstick and casing therefor, as shown.
